Fig. 1

Fig. 2

FIG. 1 is a perspective view of a building complex showing my new design; and

FIG. 2 is a top plan view of the building complex illustrated in FIG. 1.

The opposite sides of the building complex not visible in FIG. 1 are the same in appearance as the sides shown in said view.

The characteristic feature of my design resides in the provision of a rectangular central building with associated tower-like buildings located at the corners thereof.

This is a division of design application Ser. No. D. 12,830, filed July 19, 1968.

I claim:

The ornamental design for a building complex, substantially as shown and described.
